UNITED STATES PATENT OFFICE

HERMAN C. STANGER, OF FORT ANN, NEW YORK

SIGNAL AND COMMUNICATION MECHANISM FOR SUNKEN SUBMARINES

Application filed July 13, 1928. Serial No. 292,431.

The present invention relates to an apparatus for use upon submarines whereby the submarines may signal vessels on the surface of the water and telephone or radio communication may be held between the vessels on the surface of the water and a disabled submarine on the bottom.

A very important object of the invention resides in the provision of an apparatus of this nature which is exceedingly simple in its construction, inexpensive to manufacture and install, strong and durable, compact and convenient in its arrangement of parts, easy to manipulate and thoroughly efficient and reliable in use and operation.

Another very important object of the invention resides in the provision of an apparatus of this nature including a buoy having signalling means therein and also means whereby telephone connections may be made therewith by a vessel on the surface of the water.

Another very important object of the invention resides in the provision of a buoy and a cable attached thereto, and means in the submarine whereby the buoy may be let up by unwinding the cable from a drum or winch and means whereby the drum or winch may be easily controlled.

A still further very important object of the invention resides in the provision of a submarine with a casing interiorly thereof and a cover for the casing forming part of the outside of the submarine, said casing housing the reel and a buoy controllable by a cable attached thereto and windable on the reel.

Another very important object of the invention resides in efficient and effective means for holding the cover of the casing water tight in a closed position and permitting quick and easy release thereof in a convenient manner.

With the above and numerous other objects in view as will appear as the description proceeds, the invention resides in certain novel features of construction, and in the combina-

tion and arrangement of parts as will be hereinafter more fully described and claimed.

In the drawing:

Figure 1 is an elevation of a sunken submarine and a vessel on top of the water showing my improved apparatus in use to provide telephonic connection between the vessel and the submarine, 50

Figure 2 is a fragmentary longitudinal section through the submarine at the bow end thereof showing my improved apparatus mounted therein, 55

Figure 3 is a transverse section showing the apparatus disclosed in Figure 2,

Figure 4 is a section taken substantially on the line 4—4 of Figure 3, 60

Figure 5 is a section taken substantially on the line 5—5 of Figure 2,

Figure 6 is an enlarged detail section showing the means for holding the cover plate closed, 65

Figure 7 is an enlarged detail sectional view of the reel structure,

Figure 8 is an enlarged detail transverse section through the hinge structure for the cover, 70

Figure 9 is an enlarged detail view showing the gearing for operating the measuring mechanism to indicate the amount of cable which is led off the reel, 75

Figure 10 is a fragmentary top plan view of the submarine showing particularly my improved apparatus with the cover in an open position,

Figure 11 is a detail vertical section through the buoy, 80

Figure 12 is an enlarged detail fragmentary elevation of the lower portion of the buoy, and

Figure 13 is an enlarged detail section taken substantially on the line 13—13 of Figure 11, 85

Referring to the drawing in detail it will be seen that the numeral 5 denotes generally a submarine which may be of any preferred or 90

conventional structure. This submarine 5 is provided in its top preferably adjacent its bow with an opening 6.

5 A flange 7 is secured to the top of the submarine 5 interiorly thereof to extend along three sides of the opening and support gasket 8. A hinge member 9 is supported along the other side of the opening at its rear side thereof in the present illustration of the invention 10 and is formed with a socket 10 and has a flange 11 for supporting the adjacent portion of the gasket 8.

The socket 10 is divided by partitions 11' and a pintle 12 is rockable through the partitions 11' and is fixed by members 14 to a cover 15 to close the opening 6 and rest on the gasket 8.

A shaft 16 is rotatable in ears 17 depending from the hinge member 9 and has sprockets 18 on the ends thereof over which are trained chains 19. Gears 20 are fixed on the shaft 16 inwardly of the sprockets and mesh with pinions 21 on the ends of the pintle 12. Brackets 22 rising from the bottom of the 25 submarine or a compartment thereof have journaled in their upper ends a shaft 23 with sprockets 24 thereon over which the chains 19 are trained and hand wheels 25 are provided at the ends of the shaft 23.

30 Obviously by turning the hand wheels 25 the shaft 16 may be rotated and the pintle 12 rocked to swing the closure 15 either to an open or closed position as desired.

A casing denoted generally by the letter 35 C includes connected side walls 26, a bottom 27 and an outwardly extending continuous top flange 28 disposed under the flange 7 and having a portion extending to a groove 29 of the hinge member 9. I beams 30 are disposed under the flange 28 and the hinge member 9 as is indicated in Figure 5.

Brackets 32 extend from a pair of opposed 45 side walls 26 so that the ends of the shaft 16 may be journaled therein. A drain cock 33 is engaged in the bottom 27.

A pair of rods 34 are slidable through bearings 35 and gland nut 36 in the bottom 27 and through bearings 37 projecting inwardly from one of the side walls against the upper 50 edge thereof. The upper ends of these rods are threaded to engage in the threaded recess bosses 38 on the free end of the cover 15.

Stop collars 39 are fixed to the rods to engage with the bearings 37. Stop collars 40 are also provided on the rods to engage with the bearings 35 to limit the downward movement of the rods 34 when they are disengaged from the bosses 38 and to prevent the threaded ends from passing downwardly all the 60 way through the bearing 37.

Hand wheels 41 are provided at the lower end of the rod. Thus it will be seen that these rods may be threaded and unthreaded for securing or releasing the cover respectively to 65 a locked or unlocked position.

A reel is mounted in the casing C and includes a shaft 45 journaled in anti-friction bearings 46 and 47 mounted in opposed side walls 26 of the casing. Oiling means 48 leads through the side walls to these bearings. Sides 49 are provided on the shaft to complete the reel. The end of the reel through the bearing 46 is provided with a longitudinally extending passage 50 terminating in an offset end 51.

75 A hand wheel 52 is provided on this end of the reel shaft exteriorly of the casing. A gland nut 53 is engaged over this end of the shaft. A gear 55 is mounted on the shaft 45 adjacent the bearing 46. An electric cable 56 is wound about the shaft 45 between the sides 49 and has a suitable number of electric conductors extending therethrough.

80 The gearing 57 is meshed with the gear 55 and operates the shaft of a measuring mechanism 58 mounted on a bracket 59 to the outside of one of the side walls so as to indicate the amount of cable led off from the reel.

85 A buoy is denoted generally by the letter B and includes a bottom section 60, a top section 61 and a supplemental section 62. The sections 60 and 61 are secured together by flanges 63 and 64 which may be welded or otherwise secured together. A transverse or diametrically disposed bar 65 is carried 90 by the section 60.

95 The section 62 extends over a disk top 66 in the section 61 and has a bell 67 suspended therein for producing an audible signal. Brackets 68 depend from the section 60 and 100 rotatably support a cylinder 69 and having a spiral exterior groove 70 therein. A clamp 71 is provided on the section 60 adjacent the cylinder 69.

105 A stuffing box inlet 72 is provided in the bottom of the section 60 for the cable from the reel which is wrapped about the cylinder 69 in the groove 70 and engaged in the clamp 71. This cylinder acts as a snubber so as to take up any shock and the like.

110 The cable extends up through a clamp 74 supported by the bar 65 and into a heat terminal box 75 having a suitable number of terminals 76 therein connected with the electric conductors of the cable. An opening 77 is formed in the box 75 and is normally plugged up to prevent the ingress of water into the box but when the buoy has reached the surface the plug is replaced by a gasket 78 so that the cable 79 from the rescue vessel 115 88 may be inserted therethrough and have its conduits engaged with the terminals 76.

120 The inner end of the cable is extended through the passage 50, out through the end of the shaft 45 having a hand wheel 52 thereon and is normally disconnected from telephones 80 in the submarine. The buoy has a cylinder 81 thereon grooved similar to the cylinder 69 so that the cable from the vessel 88 may be wrapped thereabout so as to take 125 130

the strain off the connections provided by terminals 76.

Some side walls of the casing are provided with windows 89 in order that the contents of the casing may be seen from the exterior thereof. The buoy when in the casing rests on springs 90 carried by brackets 91 on the side walls of the casing.

Assuming that the buoy is in the casing and the cable is wound on the reel and the cover is closed and that the submarine has become disabled and is in distress on the bottom of the water. It will be seen that the crew may release the cover by turning the rods 34 and then may open the cover by rotating the shaft 23. Water will then rush into the casing C and cause the buoy to float up to the surface of the water.

An attendant may control the speed of the rising of the buoy by means of the hand wheel 52 and can very readily tell when the buoy has reached the surface of the water by the change of the speed of the let off from the reel and when the buoy has reached the top surface of the water the wheel 52 may be tied to a lug 95 by means of a chain or in any other suitable manner. The buoy will be prevented from floating away too far. The bobbing of the buoy on the surface of the water will naturally ring the bell therein. If desired a radio set may be incorporated in the buoy so that an SOS signal may be sent out.

When the buoy is discovered by the rescue vessel 88 telephonic connections are made therewith as explained and telephonic connections will be made by the crew in the submarine between the telephone 80 and the cable are suitable connections 96.

The cable is normally disconnected from the telephone to prevent twisting of the cable when the reel is unwinding.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it will attain the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination with a submarine, of a casing in the submarine, a reel and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod,

the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod.

2. A signal buoy of the class described including hollow body, a box on the upper portion of the hollow body, electrical connections in the box, a cable extending through the body connected with the connections, means for anchoring the cable interiorly of the body, stuffing box means through which the cable extends through the bottom of the buoy, a clamp on the bottom of the buoy for the cable, brackets extending from the bottom of the buoy, a cylinder rotatable in the brackets and said cable being wound thereabout.

3. A signal buoy of the class described including hollow body, a box on the upper portion of the hollow body, electrical connections in the box, a cable extending through the body connected with the connections, means for anchoring the cable interiorly of the body, stuffing box means through which the cable extends through the bottom of the buoy, a clamp on the bottom of the buoy for the cable, brackets extending from the bottom of the buoy, a cylinder rotatable in the brackets and said cable being wound thereabout, said cylinder having a spiral groove to receive the cable.

4. A signal buoy of the class described including hollow body, a box on the upper portion of the hollow body, electrical connections in the box, a cable extending through the body connected with the connections, means for anchoring the cable interiorly of the body, stuffing box means through which the cable extends through the bottom of the buoy, a clamp on the bottom of the buoy for the cable, brackets extending from the bottom of the buoy, a cylinder rotatable in the brackets and said cable being wound thereabout, said cylinder having a spiral groove to receive the cable, said body being dished downwardly at the top thereof, and a section over said downwardly dished top, and a bell suspended from the section.

5. In combination with a submarine, of a casing in the submarine, a reel and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod,

hand wheel exteriorly of the casing operatively connected with the reel, and a lug on the casing so that the hand wheel may be tied thereto.

6. In combination with a submarine, of a casing in the submarine, a reel and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod, a hand wheel exteriorly of the casing operatively connected with the reel, and a lug on the casing so that the hand wheel may be tied thereto, a measuring mechanism exteriorly of the casing, and gearing operatively connecting the measuring mechanism with the reel to ascertain the amount of cable let off from the reel, said reel including a shaft, one end of which is provided with a longitudinal extending passage through which the cable extends, a telephone in the submarine with which the cable is engageable, and connections in the buoy with which the cable is connected, said cable housing electrical conductors, said buoy having brackets extending from the bottom thereof, a cylinder rotatable in the brackets having a spiral groove therein, the cable being wrapped about the cylinder in the groove to take the strain off the electrical connection.

7. In combination with a submarine, of a casing in the submarine, a reel and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod, a hand wheel exteriorly of the casing operatively connected with the reel, and a lug on the casing so that the hand wheel may be tied thereto, a measuring mechanism exteriorly of the casing, and gearing operatively connecting the measuring mechanism with the reel to ascertain the amount of cable let off from the reel, said reel including a shaft, one end of which is provided with a longitudinal extending passage through which the cable extends, a telephone in the submarine with which the cable is engageable, and connections in the buoy with which the cable is connected, said cable housing electrical conductors, said buoy having brackets ex-

tending from the bottom thereof, a cylinder rotatable in the brackets and having a spiral groove therein, the cable being wrapped about the cylinder in the groove to take the strain off the electrical connection.

8. In combination with a submarine, of a casing in the submarine, a reel, and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod, a hand wheel exteriorly of the casing operatively connected with the reel, and a lug on the casing so that the hand wheel may be tied thereto, a measuring mechanism exteriorly of the casing, and gearing operatively connecting the measuring mechanism with the reel to ascertain the amount of cable let off from the reel, said reel including a shaft, one end of which is provided with a longitudinal extending passage through which the cable extends, a telephone in the submarine with which the cable is engageable, and connections in the buoy with which the cable is connected, said cable housing electrical conductors, said buoy having brackets extending from the bottom thereof, a cylinder rotatable in the brackets and having a spiral groove therein, the cable being wrapped about the cylinder in the groove to take the strain off the electrical connection.

9. In combination with a submarine, of a casing in the submarine, a reel and a buoy housed in the casing, a cable wound about the reel and connected with the buoy, a cover for the casing forming part of the wall of the submarine, means for hingedly mounting the cover, chain and sprocket means for opening and closing the cover, rods rotatably mounted in the casing and accessible interiorly thereof and threadedly engageable with the cover to lock the same in a closed position, means for limiting the upward and downward sliding movement of the rod, a hand wheel exteriorly of the casing operatively connected with the reel, and a lug on the casing so that the hand wheel may be tied thereto, a measuring mechanism exteriorly of the casing, and gearing operatively connecting the measuring mechanism with the reel to ascertain the amount of cable let off from the reel, said reel including a shaft, one end of which is provided with a longitudinal extending passage through which the cable extends, a telephone in the submarine with which the cable is engageable, and connections in the buoy with which the cable is connected, said cable housing electrical conductors, said buoy having brackets ex-

cable is connected, said cable housing electrical conductors, said buoy having brackets extending from the bottom thereof, a cylinder rotatable in the brackets and having a spiral groove therein, the cable being wrapped about the cylinder in the groove to take the strain off the electrical connection, a second spiral groove cylinder on the top of the buoy, said casing having windows in side walls thereof.

10 In testimony whereof I affix my signature.
